THOMAS ROSE, OF OXTON, AND ROBERT EMERSON GIBSON, OF NEW BRIGHTON, ENGLAND.

Letters Patent No. 93,124, dated July 27, 1869.

IMPROVEMENT IN MACHINERY FOR BREAKING COTTON-SEED.

The Schedule referred to in these Letters Patent and making part of the same.

To all to whom it may concern:

Be it known that we, THOMAS ROSE, of Oxtón, and ROBERT EMERSON GIBSON, of New Brighton, both in the county of Chester, England, have invented certain new and improved Machinery for Breaking Cotton-Seed; and we do hereby declare that the following is a full and exact description thereof, reference being had to the accompanying sheet of illustrative drawings, forming part of this specification, and to the figures and letters thereon; that is to say—

Our improved machinery has been devised and perfected for the purpose of breaking cotton-seed, more particularly that kind or class of it hitherto almost valueless, known as "coated seed," in such manner, that the kernels or oil-yielding portions can be easily separated from the husks and fibre.

In its passage through our machinery, the cotton-seed is subjected to a tearing-action, of such a character that the kernels are sufficiently disintegrated, or ground into meal, to allow of their easy removal from the husks and fibre, by sifting.

The meal obtained from a given weight of seed in this way, (and such meal is the desired product,) will yield a larger quantity of oil, on being subjected to pressure or otherwise manipulated, than the whole seed, treated in any usual way, would have given out.

That the construction and action or mode of operation of our said machinery may be clearly seen and understood, and that others acquainted with mechanism for operating on seeds may be enabled to make and carry our improvements into effect, we will refer to Figures 1, 2, 3, and 4, on the sheet of drawings here-to attached, premising that in all these views like letters denote the same parts.

Figure 1 represents a view in longitudinal elevation,

Figure 2, an end elevation,

Figure 3, a plan, and

Figure 4, an end view of one of the segments forming the circumference of the breaking-rolls.

A denotes the supporting-frame.

This consists of side-pieces *a* and ties *a'*.

B B', plumber-blocks, adjustable by the set-screws *b*, bushed, to carry the shafts C C' of the breaking-up serrated rolls.

These rolls are here shown constructed with radial arms *c* *c'*, and circumferential rings *c* *c'*, whereto segmental pieces *c'*, with serrated surfaces are bolted. One of these segmental pieces is shown full size by fig. 4, and the form of "teeth" which answers best is illustrated.

Although we prefer to construct the rolls in segments, as iron and steel can be easily cast into that form in chill-moulds, it will be obvious the said rolls can be cast in one or more lengths, with the serrations, or the serrations can be formed afterwards, in chill-moulds, or otherwise.

To make the circumferences of the said rolls rotate at differential speeds—and such speed of rotation is of great importance, as regards breaking quantity, for by

it the seed, in passing between the serrated surfaces, is subjected to a dragging-tear—they are geared by toothed wheels D and D', secured on *c* and *c'*, of different diameters.

In practice, we prefer a speed of four to one in the surface of the rolls; but we do not confine ourselves to any speed, whether differential or the same. Instead, however, of obtaining it by gearing of different diameters, we may make the rolls themselves of different diameters; but this we do not consider so efficacious as the arrangement just described and shown on the drawings.

E is the driving-pulley, receiving motion from any convenient line of shafting or power.

To keep the serrated surfaces clean, we employ cylindrical brushes F F', of coir or other strong fibre, and make them rotate by bands or cords *f*, passed over pulleys *f* *f'*, on the ends of the axis of *c* *c'*, and over pulleys *f* *f'*, on the ends of the axis of the brushes.

When the said machinery or machine is at work, the cotton-seed is fed from the hopper Z, to or between the serrated rolls. These, as they rotate towards each other, as indicated by the arrows, so break it up, the distance between them being tempered to the size and condition of the seed, by the screws *b*, that when the gross product of kernels, in the state of meal and husks and fibre, is discharged underneath, it is only necessary to employ ordinary sifting-screens, to remove the meal.

The shallowness of the indentations in the rolls, and the great obliquity of the surfaces of these indentations, greatly facilitate the discharge of the crushed seed, and render the effect of our machine very different from that of any machine with projecting pins, or with any analogous deep or rectangular spaces between the projections. Our machine will serve in some cases without clogging, even if the brushes F F' are omitted, or are not operated. But we esteem it much better to employ the brushes in combination, in all ordinary conditions of the kernels, and husks of the seeds.

Having now described the nature of our said invention, the construction of the machinery, and the manner of employing the same in practice, we would have it understood, that what we claim as of our invention, is—

The shallow notched rolls and hopper, as specified, combined and arranged relatively to each other and to the clearing-brushes F F' as herein set forth.

In testimony whereof, we have hereunto set our names, in presence of two subscribing witnesses.

THOMAS ROSE.
